UNITED STATES PATENT OFFICE.

STEPHEN L. DAVIDSON AND CHESTER L. DAVIDSON, OF VIRDEN, ILLINOIS.

CAR-COUPING.

SPECIFICATION forming part of Letters Patent No. 268,633, dated December 5, 1882.

Application filed May 13, 1882. (Model.)

To all whom it may concern:

Be it known that we, STEPHEN L. DAVIDSON and CHESTER L. DAVIDSON, of Virden, in the county of Macoupin and State of Illinois, have invented a new and Improved Car-Coupling, of which the following is a full, clear, and exact description.

The invention consists in the combination, with a draw-head having a recessed side wing 10 for receiving the coupling-pin when the same is not in use, of a longitudinally-movable transverse shaft held on the end of the car, and provided with an arm to which the coupling-pin is pivoted.

15 The invention also consists in the combination, with a draw-head, of a chain attached to a transverse shaft on the end of the car and to the link in the draw-head, which chain passes through an aperture in the draw-head, 20 whereby the link can be drawn partially into the draw-head and held horizontally by winding part of the chain on the shaft.

Reference is to be had to the accompanying drawings, forming part of this specification, 25 in which similar letters of reference indicate corresponding parts in all the figures.

Figure 1 is a plan view of the ends of two cars provided with our improved car-coupling. Fig. 2 is a longitudinal sectional elevation of the 30 same on the line $x x$, Fig. 1. Fig. 3 is a cross-sectional elevation of the winged draw-head with the two recesses and apertures.

The draw-head A is provided with a link-receiving aperture and with a pin-receiving 35 aperture in the usual manner, and in the top of the draw-head a recess, B, with inclined sides, is formed for the purpose of guiding the coupling-pin C in the corresponding aperture in the draw-head. The draw-head A is provided at its outer end with a wing, D, provided with an aperture from top to bottom, the sides of which are inclined or beveled. The coupling-pin C is pivoted to the end of arm E of a shaft, F, passing loosely through 40 longitudinal eyes or loops G on the lower part of the end of the car, so that this shaft can be moved in the direction of its length and can be turned on its axis, which loops G project from the end of the car as far as the buffer-

spring lets the draw-head move under or into 50 the car, so that the shaft F can also be moved forward and backward sufficiently to permit passing the pin into the pin-opening. The shaft F is provided with handles or rings H at the ends to facilitate operating it. The 55 draw-head I at the opposite end of the car is provided with a link-receiving aperture and a coupling-pin-receiving aperture in the usual manner. A chain or equivalent device, J, is attached to the inner end of the link K, passes 60 through an aperture, L, in the top of the draw-head, and is attached to a shaft, M, journaled on the end of the car or passing through loops or eyes O, which shaft is provided at the ends with rings or handles N. By winding the 65 chain J on the shaft M the link K is drawn into the draw-head I and is held horizontally. When the cars come together the link passes into the link-opening of the draw-head A, and the pin C is lowered by turning the shaft F. 70 The pin C passes through the link K, and thereby the cars are coupled. If the cars are to be uncoupled, the pin C is raised, the shaft F is moved in the direction of its length, and the pin C is lowered into the recess in 75 the wing D, so as to be out of the way and permit the coupling-link to enter the draw-head A.

The cars can be provided at both ends with draw-heads A, or at one end with a draw-head, A, and at the opposite end with a draw-head, I, as may be desired.

Having thusfully described our invention, we claim as new and desire to secure by Letters Patent—

1. The draw-head A, constructed with a recess, B, in its top, and with a recessed wing, D, substantially as shown and described, and for the purpose set forth.

2. The combination, with the shaft F, carrying pin C by its arm E, of the elongated loop-bearings G to insure dropping of the coupling-pin in the apertures of the longitudinally-sliding draw-head, substantially as shown and described.

3. The combination, with the draw-head A, provided with a recessed wing, D, of the coupling-pin C, and the longitudinally-mov-

able shaft F, provided with an arm E, to which the coupling-pin is pivoted, substantially as herein shown and described, and for the purpose set forth.

5 4. The combination, with the draw-bead I, of the link K, the chain J, and the shaft M on the end of the car, substantially as herein

shown and described, and for the purpose set forth:

STEPHEN L. DAVIDSON.
CHESTER L. DAVIDSON.
